FIRST AID KIT BOX

Brock F. Brockway, Mill Valley, Calif., assignor to E. D. Bullard Company, Sausalito, Calif.

Filed May 31, 1968, Ser. No. 12,165

Term of patent 14 years

Int. Cl. D3—99

U.S. Cl. D87—1

FIG_2

FIG_1

FIG_3

FIG_4

FIG_5

FIG_6

FIG. 7

FIG. 1 is a front elevation view of a first aid kit box showing my new design;

FIG. 2 is a top view thereof;

FIG. 3 is a bottom view thereof;

FIG. 4 is a back view thereof;

FIG. 5 is an elevation view of the right side thereof, the left side being a mirror image of FIG. 5;

FIG. 6 is a top plan view of the interior thereof in a fully open condition; and

FIG. 7 is a sectional view thereof taken along line 7—7 of FIG. 6.

I claim:

The ornamental design for a first aid kit box, as shown and described.
